BUILDING CONSTRUCTION

Filed Oct. 18, 1926

UNITED STATES PATENT OFFICE

JAMES F. LOUCKS, OF CLEVELAND, OHIO, ASSIGNOR TO DETROIT STEEL PRODUCTS COMPANY, OF DETROIT, MICHIGAN, A CORPORATION OF MICHIGAN

BUILDING CONSTRUCTION

Application filed October 18, 1926. Serial No. 142,322.

This invention relates to building constructions and more particularly to constructions embodying sheet metal units and which units are adapted, when assembled, to produce a light but strong metal foundation for roofs, floors, partitions, etc.

It is the general purpose and object of the invention to provide a construction unit of the character referred to which will enable 10 roofs, floors, partitions, etc., embodying sheet metal foundations, to be produced at a relatively low cost; to provide a construction which will enable the units to be assembled quickly and conveniently, in a manner analogous to shingling or weather-boarding and with the preservation of leak-proof joints; also to provide an extremely strong construction of such sheet-metal structure, as well as to provide a structure, so formed 20 to enable it to afford an efficient support for sheets of insulating cementitious or fibrous material. The invention is in some respects similar to that covered by the patent to Harry Gillett and myself, issued February 23, 1926, 25 No. 1,574,586.

In the drawing forming part hereof, Fig. 1 represents a perspective sectional view of a portion of a sheet metal unit constructed in accordance with my invention; Figs. 2 and 3 details in inverted perspective of the top and bottom of two of such units, prior to overlapping the same; Fig. 4 a detail in sectional elevation of the two units shown in Figs. 2 and 3, prior to overlapping the same; 35 Fig. 5 a view similar to Fig. 4 showing the two units overlapped and Fig. 6 a detail in transverse section through a roof structure embodying my invention.

Describing the various parts by reference 40 characters, A denotes one of the units, the same consisting of a flat metal sheet 1, to one surface of which are secured, preferably by spot-welding, hollow triangular ribs B. Each of these ribs has its base 2 remote from 45 the body of the sheet, and the convergent sides 3 are provided each with a lateral flange 4 by which the rib may be conveniently spot-welded to the sheet 1. The sheet may be of any desired length and the ribs 2 of proper 50 dimensions to constitute the supporting

beams for the sheet. One edge of the sheet 1 is bent down, forming a flange 5, while its opposite edge is secured to the nearer flange 4 only of the rib B at such edge, exposing the longitudinal slot 6 between the flanges 4 of such rib for the insertion of the flange 5 of the adjacent sheet, as shown in Fig. 6. It will be noted that the distance between the flange 5 and the adjacent rib B is approximately equal to the distance between the centers of two adjacent ribs. This will insure equidistant spacing between the ribs on the connecting units.

In using my sheet-metal support for roofing or flooring purposes, the ribs B may rest 55 upon joists or similar supports, one of which is indicated at 7, being secured thereto by nails 8, which are conveniently driven into the joists through the ribs B. When a course has been completed by assembling side-by-side 60 a sufficient number of the sheets or units A, the next succeeding course of sheets or units may be assembled with the one just laid, by overlapping the ends of the sheets of one course upon the adjacent ends of the corresponding sheets of the next course. Assuming 65 that the courses are used for roofing purposes, the ribs B will preferably be of the same length as the sheets 1, but will be secured thereto in such manner that one end 70 of each rib will project beyond one end of the sheet with the other end a corresponding distance behind or overhung by the opposite end of the sheet. This will enable the sides of the projecting parts of the ribs to be sprung 75 apart or squeezed together in order to receive therewithin, or to be received within, the ends of the ribs of the cooperating sheet in the course thereabove or therebelow, the lower ends of the sheets of one course overlapping 80 the upper ends of the sheets in the subjacent course.

The manner in which two courses of units may be assembled so as to provide a shingling construction is shown in detail in Figs. 2-5 inclusive. It is preferred to provide the shingling effect in the courses by having the ends of the sheets or units A in an upper course overhang at their lower ends the ribs B thereon, while the ribs project beyond the 100

upper ends of such sheets or units—as indicated in Figs. 2-5. The upper ends of the ribs on a lower course or sheet are narrowed by bending the base wall 2 upwardly or toward the body of the sheet and by crimping the sides 3 toward each other, as shown at 2^a and 3^b. This provides a narrow extension B' for each rib which extension is of less height or depth than the depth of the body of the rib B, thus enabling such narrowed extension to be inserted into the body of the rib B on the cooperating sheet in the course thereabove. The flanges 4 are cut off, preferably at about the junction of the narrowed extension B' of each rib with the body thereof. This enables the tongues or projections B' to be inserted in the ends of the ribs on the corresponding sheet in the course thereabove with the lower end of such upper sheet overlapping the upper end of the sheet carrying such projections and with the flanges on such upper and lower sheets to abut.

After the desired area has been covered by the sheet metal units 1, a coating 9 of asphalt or other suitable adhesive agent may be applied to the upper surfaces of the units, after which a coating 10, preferably of insulating material such as sheet cork or a more or less heavy fiber sheet made from sugar cane and known to the trade as "Celotex", is applied to the asphalt coating and pressed down on top of the units 1, whereby the coating or covering 10 is adhesively united to the sheet metal units. Where the material of the coating 10 is apt to be affected by weather conditions a coating 11 of any standard waterproofing material may be applied thereto.

One of the great advantages of my invention is that the metal sheets 1 may be produced quickly and cheaply by an ordinary rolling operation and that the ribs B may also be produced by a rolling operation, the ribs being secured to the sheets 1 in a rapid and economical manner by the spot-welding operation referred to hereinbefore, such operation also enabling the ribs to be spaced apart any desired distance upon the metal sheets 1, without the necessity for the use of special rolls to produce sheets having such differently-spaced ribs thereon. The shape of the ribs results in great strength for the sheets or units, the ribs serving as non-collapsible load-sustaining beams or trusses when resting on joists or purlins. This enables me to employ very light-gage metal for the sheets of the units and heavier-gage metal for the ribs, and without the necessity for relying upon the strength of the fireproofing or other material applied thereto.

In the form of my invention shown herein, each sheet or unit comprises a continuous flat surface, enabling me to use a covering of sheet-insulating material having practically no inherent strength, without danger of

the same breaking through into the hollow ribs when subjected to moving weights.

Having thus described my invention, what I claim is:

1. A sheet metal foundation for building construction, the same comprising a continuous metal sheet having a plurality of flanged hollow triangular sheet metal reinforcing ribs, all of the same shape secured to and projecting from one face thereof, a flange of one of said ribs projecting beyond the edge of said sheet and adapted to serve as a support for an adjacent sheet. 70

2. A sheet metal foundation for building construction, the same comprising a continuous metal sheet, and a plurality of spaced hollow triangular sheet metal reinforcing ribs each side of which is provided with a flange by means of which the said ribs are secured to one side of said sheet, the said ribs projecting beyond one end of the said sheet and having their opposite ends behind or overhung by the opposite end of the sheet. 80

3. A sheet metal foundation for building construction, the same comprising a continuous metal sheet, and a plurality of spaced hollow triangular sheet metal reinforcing ribs each side of which is provided with a flange by means of which the said ribs are secured to one side of said sheet, the said sheet having at one lateral edge thereof a flange extending substantially parallel with the rib extending adjacent thereto and having a rib secured to the opposite edge, with a slot formed between the sides of said rib, 90 and one of the flanges of said rib extending beyond such edge. 100

4. A sheet metal foundation for building construction, the same comprising a continuous metal sheet, and a plurality of spaced hollow triangular sheet metal reinforcing ribs secured to one side of the said sheet, the said ribs projecting beyond one end of the said sheet and having their opposite ends behind or overhung by the opposite end of the sheet. 105

5. A sheet metal foundation for building construction comprising a continuous metal sheet having spaced hollow triangular ribs secured thereto and projecting from one side thereof, the ribs extending beyond one end of the said sheet and having their opposite ends behind or overhung by the opposite end of the sheet, one end of each rib being contracted whereby it may be inserted into the 115 open end of a rib on a like adjacent sheet. 120

6. A sheet metal foundation for building construction comprising a continuous metal sheet, a plurality of spaced hollow triangular sheet metal ribs the sides of which are provided each with a flange whereby the ribs are secured to one side of said sheet, the said ribs projecting beyond one end of the said sheet and having their opposite ends behind or overhung by the opposite end of the sheet, 125

each rib having its projecting end contracted for insertion into the open end of a rib on a like adjacent sheet, and each rib also having an end portion projecting beyond the

of said sheet and having a flange positioned to support an adjacent sheet.

In testimony whereof, I hereunto affix my signature.

JAMES F. LOUCKS. 70

5 flanges thereof to facilitate the telescoping connection between the ribs on adjacent units.

7. A sheet metal foundation for building construction comprising a continuous metal sheet, a plurality of spaced hollow triangular

75

10 sheet metal ribs the sides of which are provided each with a flange whereby the ribs are secured to one side of said sheet, the said ribs projecting beyond one end of the said sheet and having their opposite ends behind or

15 overhung by the opposite end of the sheet, each rib having its projecting end contracted for insertion into the open end of a rib on a like adjacent sheet.

30

8. A sheet metal foundation for building 20 construction the same comprising a continuous metal sheet, and a plurality of spaced hollow triangular sheet metal ribs the sides of which are provided each with a flange by means of which the said ribs are secured to 35 one side of the said sheet, the said ribs projecting beyond one end of the said sheet and having their opposite ends behind or overhung by the opposite end of the sheet, the projecting ends of the ribs being contracted 40 for telescopic connection with the open ends of the ribs on adjacent sheets and such reduced ends projecting beyond the flanges of their respective ribs thereby to facilitate the assembling of adjacent sheets with telescopic 45 connections between the ends of the ribs on said sheets and with the lower end of the upper sheet overlapping the upper end of the lower sheet.

9. A sheet metal foundation for building 40 construction, the same comprising a metal sheet having a plurality of reinforcing ribs, substantially channel shaped in cross section, secured to and projecting from one face thereof, said ribs having flanges, each of said 45 flanges having one surface lying in the plane of said face, one of said flanges of one of said ribs projecting beyond one edge of said sheet.

10. A sheet metal foundation for building construction, the same comprising a metal 50 sheet having a plurality of reinforcing ribs, substantially channel shaped in cross section, secured to and projecting from one face thereof, said ribs having flanges, each of said flanges having one surface lying in the plane 55 of said face, one of said flanges of one of said ribs projecting beyond one edge of said sheet, the opposite edge of said sheet having a down-turned flange thereon.

11. A foundation for building construction, comprising a sheet, and a plurality of 60 spaced hollow triangular reinforcing ribs having sides converging toward said sheet and flanges on said sides by means of which said ribs are secured to one side of said sheet, 65 one of said ribs projecting beyond an edge
